W. Clark,

Bedstead Fastening,

No 19,544.

Patented Mar. 9, 1858.

UNITED STATES PATENT OFFICE.

WILLIAM CLARK, OF WEYMOUTH, OHIO.

BEDSTEAD-FASTENING.

Specification of Letters Patent No. 19,544, dated March 9, 1858.

To all whom it may concern:

Be it known that I, WILLIAM CLARK, of Weymouth, in the county of Medina and State of Ohio, have invented certain new and useful Improvements in Bedstead-Fastenings; and I do hereby declare the following to be a full and exact description thereof, reference being made to the accompanying drawings, in which—

10 Figure 1 is a perspective view of a bedstead with my improvement attached. Figs. 2, 3, and 4, enlarged views of the fastening, detached from the bedstead, and Fig. 5, a section of the bedstead and fastening.

15 Like letters denote like parts in the several views.

A represents the side rails, B, the end rails, C, the posts. On the upper side of the rails A, are secured the bolts D, which 20 extend a short distance beyond the rails as seen in Fig. 5. In the sides of the posts facing the ends of the rails A, is sunk a clamp or washer E, even with the face of the post, Figs. 1 and 5. The red lines F, 25 show the position of the rails A, in order to introduce the bolt into the slot E' of the clamp, and also to withdraw them from the clamp. This raised position of the rail is obtained by the hinge joint at G, Fig. 1, 30 which is made sufficiently strong for all purposes and placed on the underside of the rail. The pin H is inserted for the purpose of preventing any lateral motion of the rails when in their proper place.

35 Fig. 2, shows the fastening or coupling, together, detached from the posts and rails. When the bedstead is secured together, the fastening assumes the position in the posts and rails, shown in Fig. 2. In this position 40 the fastening cannot be separated, as the head D' extends above the slot E' on the inside, as seen in Fig. 5, and the more pressure there is vertically upon the side rails the more firmly will the fastening be held 45 as the tendency of the pressure upon the side rails is to press the upper part of the head D' up under the flange B'', and the lower ends of the rails to press against the posts. The shoulder D'' resting upon the

lower edge of the slot E', forms a fulcrum 50 for these two points.

Fig. 3 represents the position of the bolt D, when the side rails are raised at F, Fig. 1, for the purpose of connecting and disconnecting, in taking down and setting up 55 the bedstead. When the bolt D, is in the position seen in Fig. 3, and the rails at F, Fig. 1, the head D' is inserted within the slot E' of the washer, the rails are then forced down to the position seen at A, Fig. 60 1, their proper place. The neck of the bolt, by this means is forced up the slot of the washer, and retained in place by the peculiar form of the fastening as before described.

65 Fig. 4 represents the bolt and washer separate.

The finger I projecting from the underside of the bolt near the head, prevents the bolt from entering too far into the washer 70 and affords greater strength to the fastening.

On the underside of the rails A, is secured a spring J at each end as seen in Fig. 1, which reaches into the post, as seen in 75 Fig. 5, where it clasps a pin K, inserted in the posts, this connection of the spring J, with the pin K, prevents the bottom of the posts from slipping out, in case there should be any tendency to do so by the action of 80 the side rails. By pressing the spring J upward, it is readily detached from the pin so that the fastening can be separated as before described. The spring will clasp the pin of its own accord, when the rails are 85 being moved from F to A.

What I claim as my improvement and desire to secure by Letters Patent is—

The arrangement of the bolt D, with the head D', and finger I, and the washer E, 90 provided with the slot E', and flange E'', in connection with the jointed rails, which are provided with springs J, and pins K, for the purpose set forth.

WILLIAM CLARK.
